UNITED STATES PATENT OFFICE.

NATHANIEL E. CHASE, OF BOSTON, MASSACHUSETTS.

GAS-HEATER.

SPECIFICATION forming part of Letters Patent No. 247,167, dated September 20, 1881.

Application filed June 11, 1881. (No model.)

To all whom it may concern:

Be it known that I, NATHANIEL E. CHASE, of Boston, in the county of Suffolk and State of Massachusetts, have invented a new and 5 useful improvement in Portable Gas-Heaters, of which the following is a specification.

My invention relates to an improvement in that class of heating devices used in connection with a gas-burner for heating liquids or 10 solid substances; and the invention consists in an adjustable support or holder provided with legs having grooved lower ends, which are made to fit upon the projecting upper edges of a cylindrical casing made open at the bottom and provided with a wire-netting at the 15 upper end, the said casing being supported by means of a frame upon the tube of a gas-burner.

Referring to the drawings, Figure 1 is a perspective view of a device embodying my invention. Fig. 2 is an elevation of a portion of the same. Fig. 3 is a top view of the supporting-frame folded.

A is a cylindrical casing, made preferably of 20 tin or sheet metal. It is entirely open at the lower end. The upper end is provided with a fine wire-netting, D.

To the lower edges of the casing A is attached a flat metal piece, a a, as shown, to 25 which is fixed a tapering tube, B, which is designed to fit over an ordinary gas-burner.

On the upper part of the cylindrical casing A is fitted a holder or support composed of two thin metal bars, C C', secured together at 30 the center by a rivet, f, and provided each with legs e e, the lower ends of which are curved or grooved, so as to engage with a projection on

the upper end of the cylindrical casing A, as shown at d d, by means of which the support or holder C C' may be readily attached to or 40 detached from the said casing.

The two bars C C' may be folded together, as shown in Fig. 3, for convenience of packing and transportation.

When in use the tube B is fitted upon a gas- 45 burner. The gas is then turned on, and passing up into the casing becomes mingled with the large volume of air in said casing, and, being ignited above the wire-netting D, produces a very intense heat. On account of the fine- 50 ness of the wire-netting the gas and air do not pass at once through the netting, but on meeting the under side of the netting a portion of the air and gas becomes deflected, and they are caused to reverberate within the casing and 55 so become thoroughly mixed before passing through the wire-netting.

What I claim as my invention is—

1. The adjustable support or holder C C', in 60 combination with the legs or supports e e, provided with the grooved ends d d fitting on the projecting edges of the casing A, as set forth.

2. The combination of the cylindrical casing A, open at the bottom and provided with the wire-netting D, the adjustable holder C C e e, 65 the frame or support a a, and tube B, all as and for the purpose specified.

In testimony whereof I have signed my name to this specification in the presence of two subscribing witnesses.

NATHL. E. CHASE.
